UNITED STATES PATENT OFFICE.

SAVERIO MINUNNO, OF BROOKLYN, NEW YORK.

COMBINATION HAND FAN.

Application filed December 16, 1927. Serial No. 240,491.

This invention relates preferably but not necessarily to a hand device which includes a vanity case and a lip stick holder, the device being provided with a fan and a motor for 5 operating it. Some of the features of the invention are applicable to the construction shown and described in my Patent No. 1,632, 556, dated June 14, 1927.

An object of the invention is to provide a 10 motor operated hand fan with convenient means for winding up the motor, which means is of extreme simplicity and is so constructed and arranged that the user of the fan may grasp the handle with the fingers of one hand 15 and wind up the motor by the use of the thumb of the said hand, so that only one hand is necessary in order to support and operate the fan.

These being among the objects of the present invention, the same consists of certain features of construction and combinations of parts to be hereinafter described and then claimed with reference to the accompanying drawings illustrating a preferred and a modified form of the invention, in which:

Figure 1 is a sectional elevation of the device, with the fan blades in using position, taken on the line 1—1, Fig. 2;

Fig. 2 is a section on the line 2—2, Fig. 1; 30 Fig. 3 is a rear elevation of the motor casing showing more particularly the preferred arrangement of the train of gears, the vanity case or receptacle being here removed for the sake of clearness;

Fig. 4 is a detail view of the stop means for 35 automatically holding the fan blades in using position, and

Fig. 5 is a section of a modified form in which a vanity receptacle or case is employed 40 to wind up the motor.

Referring to Figs. 1 to 4 inclusive the improved combination device includes a casing or frame 10 which is preferably cylindrical in shape and encloses a suitable train of gears 45 11 which are mounted on the back plate 12 of the fan motor. A driven shaft 13 of the motor extends through the front of the casing 10 and on it are mounted the fan blades 14, 15 and 16, preferably three in number, but the number may be varied. The fan blades are preferably mounted upon a sleeve 13^a which may be suitably held rigidly on the driven shaft 13. One of the fan blades 14 is provided with a stop shoulder 17 and that fan blade is 55 rigidly fixed to the sleeve 13^a while the other

fan blades 15, 16 are pivoted on the sleeve. The fan blades 15, 16 are provided with abutting shoulders 18, 19, respectively, which are adapted to come in contact with the stop 17 when the motor is operating the shoulders 18, 19 being held against the stop 17 by centrifugal action. A central shaft 20 is fixed in the casing 10 in a suitable manner and on it is mounted the hub 21 of one of the gears of the train. A spring barrel 22 encloses the coiled winding spring 23 which is fixed at one end to the barrel and at the other end to the hub 21. The outer wall of the spring barrel 22 takes the form of a ratchet wheel 24 having teeth 25.

An operating lever 26 is pivoted at its inner end upon the stationary shaft 20, it being confined thereon as by a retaining pin 27. At a point within the casing 10 there is secured to the manually operable lever 26 a spring pawl 26^a, the toe of which is adapted to positively engage the teeth 25 of the ratchet so as to rotate the ratchet when the lever 26 is oscillated. The lever 26 projects a slight distance beyond the periphery of the casing 10 and is 70 provided with a button or knob 28 which is adapted to be engaged by the thumb of the operator. The major portion of the lever oscillates within the casing 10, and the short outer end thereof extends through a curved slot 29 in the wall of the casing, so that the lever may be oscillated without interference. The length of the lever is preferably but a little longer than the distance between the shaft 20 and the periphery of the casing and 75 the lever operates concentrically with the casing. A pull spring 30 is secured at one end to the back plate 12 and at its other end to an offset portion 30^a of the lever so that normally the lever is pulled towards one end of 80 the slot 29, the offset portion 30^a being pulled into engagement with a stop 32 projecting from the back plate 12. Extending in the same direction as the pawl 26^a there is a spring detent 31 which is fixed to the back 85 plate 12, its free end entering behind the shoulders of the ratchet teeth as the ratchet is turned, so as to prevent backward rotation of the ratchet.

As shown more clearly in Fig. 2 a cylindrical flange 33 is adapted to frictionally seat in a rabbet groove 34 of the casing 10, that is, there is a snap fit. The flange 33 may be considered to be a part of the wall of the casing, although in reality it is a projecting 100 105 110

flange of a vanity case or receptacle 35 which is thus mounted at the back of the casing 10. This vanity case may be of any suitable or preferred construction and is provided with a hinged cover or closure 36 which may bear a mirror 37 on its inner side. A suitable compact 38 is positioned in the receptacle 35 which also may contain a powder puff 39. It will be seen that the vanity case or receptacle is of approximately the diameter of the casing 10 and does not objectionably protrude therefrom or interfere with the motor. Its lines blend with the casing 10 so that a combined motor casing 10 and vanity case are provided with harmonious proportions and design. In the organized device the fan will be located at the front of the casing and the vanity case or receptacle at the back of the casing, with the motor mechanism between them and hidden from view.

The face plate 40 of the motor is secured to the casing 10 in any desirable removable manner and is provided with a lateral ear 41 located adjacent a hole 10^a in the casing and to the ear 41 is rigidly secured the inner end of a handle 42 which projects through the opening 10^a, so as to be in convenient position for grasping by the hand.

It will be seen that when the fingers of one hand are used to grasp the handle 42, the thumb of that hand will be in position to conveniently press upon the button 28 at the outer end of the lever 26, and that as the lever is oscillated, the button 28 will move concentric with the periphery of the casing in both its forward and backward movements. Normally the manual lever 26 extends laterally away from the axis of the handle at an angle of somewhat less than ninety degrees, so that the button 28 will be normally positioned conveniently for engagement by the thumb, as only a short portion of the lever 26 projects from the casing 10 so that the lever is not at all obtrusive in appearance. Referring more particularly to Fig. 1 it will be seen that the handle 42 is provided with a longitudinal recess 43, the outer end of the wall of which is provided with a screw thread 44. The hollow handle 50 is adapted to contain a holder 45 for a lip stick 46, and the holder is provided with a screw thread 47 to engage the thread 44 so that the lip stick may be conveniently removed from the handle or replaced. When replaced it is entirely within the handle, except for a milled head 48 which abuts the outer end of the handle when the lip stick holder is properly inserted into the handle.

It will be seen that by reason of the preferred combination of parts a hand fan is provided which will recommend itself to females, inasmuch as it supports in convenient position a vanity case and a lip stick, and it is not necessary to discontinue the intermittent winding up of the motor of the fan in

order to gain access to the contents of the vanity case and to the lip stick.

In Fig. 5 a modification is illustrated, wherein instead of a vanity case which is fixed positively to the casing of the motor, a vanity case 49 is provided which has a circular flange 50 which fits loosely yet snugly within the flange of the motor casing, thereby permitting the vanity case 49 to be rotated when it is grasped by one hand, the other hand in that case taking hold of the handle of the fan. In order to operate the motor by rotating the vanity case, the inner wall of the same is connected by suitable screws 51 with the ratchet of the motor, so that it is only necessary to turn the vanity case instead of engaging the teeth of the ratchet. The other features may be the same, that is the motor, the fan and the construction of handle providing for a lip stick, as in the preferred embodiment of the invention; and the ratchet may be omitted.

It is obvious that the invention is susceptible to more or less modification, and I do not limit myself in this respect, except as defined in the appended claims.

What I claim, is:

1. A device of the class described, comprising in combination, a frame or casing, a spring motor mounted therein, a fan driven by the driven shaft of the motor, a ratchet wheel and detent for winding up and restraining the spring, a mounting shaft on which the ratchet wheel is mounted to turn, a thumb-lever pivoted on the mounting shaft and provided with a pawl for engaging the ratchet teeth to wind the spring, a handle on the frame, and stop means for normally positioning the lever laterally of the handle for depression of the lever by the thumb while the other fingers grasp the handle.

2. A device of the class described, comprising in combination, a frame or casing, a motor mounted therein and having a winding spring, a fan driven by the driven shaft of the motor, a ratchet wheel and detent for winding up and restraining the spring, a fixed shaft on which the ratchet wheel is mounted to turn, a thumb-lever pivoted on the fixed shaft and provided with a pawl for engaging the ratchet teeth to wind the spring, a handle on the frame, and stop means for normally positioning the lever laterally of the handle for depression of the lever by the thumb while the other fingers grasp the handle, the lever being relatively short with respect to the handle and positioned near the inner end of the handle, and but slightly longer than the distance from the fixed shaft to the wall of the frame.

3. A device of the class described, comprising in combination, a frame or casing, a motor mounted therein and having a winding spring, a fan driven by the driven shaft of the motor, a ratchet wheel and detent for wind-

ing up and restraining the spring, a fixed shaft on which the ratchet wheel is mounted to turn, a thumb-lever pivoted on the said shaft and provided with a pawl for engaging 5 the ratchet teeth to wind the spring, a handle on the frame, the thumb-lever projecting slightly from the frame and having a button or knob on its free outer end, a spring for

lifting the lever upwardly away from the handle, and stop means for positioning the 10 lever normally away from the handle for depression of the button and lever by the thumb while the other fingers grasp the handle.

SAVERIO MINUNNO.
